UNITED STATES PATENT OFFICE.

EDWARD H. AMET, OF CHICAGO, ILLINOIS, ASSIGNOR TO H. A. STREETER,
OF SAME PLACE.

ELECTRIC STEAM-GOVERNOR.

SPECIFICATION forming part of Letters Patent No. 341,368, dated May 4, 1886.

Application filed January 28, 1886. Serial No. 190,040. (No model.)

To all whom it may concern:

Be it known that I, EDWARD H. AMET, a citizen of the United States, residing in Chicago, in the county of Cook and State of Illinois, have invented a new and useful Improvement in Electric Steam-Governors, of which the following is a specification.

My invention relates to governors or devices for automatically controlling the amount of current generated by a dynamo-machine by governing or regulating the position of the valve of the engine by which the dynamo is driven, and more particularly to improvements upon the electric steam-governors heretofore patented to me in Letters Patent No. 326,934, of September 29, 1885, and No. 292,397, of January 22, 1884.

In my present improvement two electro-magnets are employed to operate the rocking lever, by which its oppositely-driven wheels are brought in connection with the valve-adjusting mechanism. These two electro-magnets are both normally cut out of circuit, and one or the other is put in circuit by a controlling-magnet in the circuit to be regulated, which magnet operates simply as a relay to open and close the circuit through one or the other of the two operating-magnets. By this means the regulator is made very sensitive and quick to respond to very slight changes in the current, as the controlling-magnet has no work to do except simply to open or close the circuits through the two operating-magnets, by which the power-driven gears or wheels upon the rocking lever are held in engagement with the mechanism by which the motion is communicated to the valve-stem.

My invention consists in the novel devices and novel combinations of devices herein shown and described, and more particularly pointed out in the claims.

In the accompanying drawings, which form a part of this specification, and in which similar letters of reference indicate like parts, Figure 1 is a side elevation of a device embodying my invention, showing also a diagram of the circuits. Fig. 2 is an enlarged detail sectional view, showing the mechanism employed to communicate motion in one direction or the other to the valve-stem. Fig. 3 is

a section taken just above the operating-magnets *v*, showing the same in plan view, and Fig. 4 is a detail rear view of the operating-magnets.

In said drawings, *A* may represent the valve-chamber of a steam-engine, and *a* the valve-stem; *A'*, the dynamo-machine, which is driven by the engine controlled by the valve *A*, and *C* is the external circuit supplied with current by said dynamo, and the amount of current on which is to be governed or regulated.

B is a controlling or relay magnet connected with the circuit *C*, and preferably included directly therein in series with the arc lamps or other working resistances on said circuit.

D and *D'* are two electro-magnets, by which the rocking lever *E* is tilted in one direction or the other, so as to bring the constantly-revolving wheels *e e'*, journaled thereon on opposite sides of its fulcrum, in engagement with the friction-wheel *F* on the shaft *f*, which communicates the motion to the valve-stem. The magnets *D* and *D'* are both normally out of circuit; but the circuit through one or the other of these magnets may be closed by the relay-magnet *B*, according as the current through said magnet *B* is greater or less than its normal or proper amount. The magnet *B* has an armature or switch-lever, *b*, which makes connection with the contact-piece *b'* or the contact-piece *b''*, or neither of said contact-pieces, according as the current on the circuit *C* is greater or less than its normal amount, or at its normal amount. A spring, *b'*, and its adjusting-screw *b'*, serve to pull the switch or armature *b* into connection with the contact-piece *b''* when the current through the controlling-magnet *B* falls below its normal or proper strength.

The mechanism by which the motion of the wheel *F* in one direction or the other is communicated to the valve-stem *a* is fully shown and described in Patent No. 326,934, to which patent reference is here made. Suffice it here to state that the shaft *f* of the friction-wheel *F* is journaled in a suitable standard, *F'*, and is provided with a beveled gear, *f'*, which meshes with a hollow beveled gear, *f''*, journaled on a bracket, *F''*, attached to the standard *F'*. This hollow beveled gear has an internal thread

which engages an external threaded sleeve, f^3 , surrounding the valve-stem, and through which the valve-stem can freely play. A stop, f^6 , secured rigidly to the valve-stem, holds this sleeve in position at one end, while a stop, f^6 , serves the same purpose at the other. A coil-spring, f^7 , is inserted between the stop or collar f^6 and the end or head of the externally-threaded sleeve f^3 , so as to prevent too sudden a movement of the valve, and to permit the valve-stem to be depressed or moved by the centrifugal governor H after the valve-stem has reached a certain limit of movement, or in case the electric-governor mechanism should fail to act for any cause—as, for example, the opening of the main circuit. The magnet D is included in the circuit or wire d , which leads from the lower contact-piece, b' , through magnet D to a binding-post, N , connected to the main circuit by a wire, n . The magnet D' is included in a circuit or wire, d' , which leads from the upper contact-piece, b^2 , through said magnet D' , and thence to binding-post N and wire n to the main circuit. The friction-wheels e and e' may be constantly driven in opposite directions in any suitable manner, but preferably by means of intermeshing gears e^2 e^3 on the shafts of said friction-wheels, one of which gears, e^3 , meshes with the gear e^4 on the shaft e^5 of the driving-pulley e^6 . This driving-pulley e^6 may receive its motion from any suitable power or moving part of the engine or dynamo. The friction-wheels e and e' should preferably have beveled or inclined faces, and the friction-wheel F should have a corresponding V-shaped groove on its periphery.

The operation is as follows: As long as the normal or proper amount of current is being generated by the dynamo-machine and flows through the controlling-magnet B on the circuit C , the switch or armature b will occupy its normal position, and thus make connection with neither contact-piece b' nor b^2 , so that both the operating-magnets D and D' will remain out of circuit. The moment, however, any excess of current is generated, or any change occurs in the external resistance, the controlling-magnet B will pull its armature or switch-lever b into connection with the contact-piece b' , and thus close the circuit d through the operating-magnet D , and thus pull that end of the rocking lever E down and bring its constantly-revolving friction-wheel e into connection with the friction-wheel F , and thus revolve the threaded nut f^2 in the direction necessary to depress the valve-stem, and thus diminish the speed of the engine until a proper amount of current is restored, when the armature b of the controlling-magnet will again resume its central or normal position and open the circuit d through the operating-magnet D . When, however, too little current is being generated or flows through the controlling-magnet B , the switch or armature b will be raised by the spring b^3 into connection with the contact b^2 , and thus close the circuit through the opposite magnet, D , and move the opposite fric-

tion-wheel, e' , into connection with the wheel F , and thus move the valve-stem in the opposite direction and increase the speed of the engine until the normal current has been again restored.

My regulator mechanism, instead of being connected with the valve-stem of a steam-engine, may be applied to regulate the position of the gate of a water-wheel, the speed-controlling devices of other motors employed to drive the dynamo-machine, and other suitable or equivalent mechanism may also be used to communicate the motion of the power-driven wheel to the valve-stem or speed-controlling device of the motor in one direction or the other, as may be required. The constantly-driven gear e^4 , which communicates motion to the gears e^3 e^2 on the tilting lever E , will have a tendency to tilt the lever, especially when one of the friction-wheels e or e' is pressed against the friction-wheel F and the valve-stem is being moved; but the pull of each of the magnets D D' is sufficient to overcome this opposing force and hold the friction-wheels e or e' and F together with the requisite pressure. This force operates of course in favor of one of the magnets and against the other—that is, it helps magnet D' to hold the friction-wheel e' against the wheel F and opposes the magnet D . The magnet D' might therefore be made slightly smaller or weaker than the magnet D ; but in practice I make both magnets of the same size, as shown in the drawings, as the disturbing influence of the gear e^4 on the lever E is comparatively slight in relation to the force of the magnets D D' . When neither of the friction-wheels e or e' is pressed against the wheel F by the magnets D or D' , the friction of the loose gears e^3 and e^2 , or the resistance offered by them to the gear e^4 , is so slight that the latter has such a very slight tendency to pull the lever E that it is inappreciable, and whatever tendency there may be is or may be balanced by the adjustment of the lever or of the armatures carried by it. It will of course be understood that this tendency of the gear e^4 to tilt the lever E has no effect whatever upon the sensitiveness of the apparatus, as its sensitiveness depends entirely upon the delicacy of adjustment of the relay-magnet B , which opens and closes the circuit through the operating-magnets D and D' . The only effect of this tilting tendency of the gear e^4 on the lever E is to require the use of larger magnets D D' than might otherwise be necessary.

In another application, No. 190,050, filed on the same day with this application, I have shown and described the relay-magnet B , the operating-magnets D D' , the rocking lever E and its oppositely-revolving wheels as applied to a current-regulator for dynamos. Such subject-matter is therefore not herein claimed.

I claim—

1. The electric steam-governor, consisting in the combination, with the valve-stem of a steam-engine, of a controlling relay-magnet,

B, connected with a circuit supplied with current by a dynamo driven by said engine, two operating-magnets, D D', normally out of circuit, said controlling or relay magnet operating to close the circuit through one or the other of said operating-magnets, according as the current is less or greater than its normal amount, a rocking lever, E, furnished with two oppositely-driven wheels, and connecting mechanism for communicating the motion of one or the other of said wheels to said valve-stem, substantially as specified.

2. The combination, with a valve-stem of a steam-engine driving a dynamo-machine, of relay-magnet B, included in the external circuit of said dynamo, operating-magnets D and D', included in normally-open circuits adapted to be closed by said relay, rocking lever E, furnished with constantly and oppositely driven wheels e and e', wheel F, shaft f, gear f', hollow internally-threaded gear f², and externally-threaded sleeve f³, connected with said valve-stem, substantially as specified.

3. The electric-current regulator, consisting in the combination, with a controlling relay-magnet connected with the circuit the current on which is to be regulated, two operating-magnets included in normally-open circuits adapted to be closed by said relay, a lever, as E, furnished with two oppositely power-driven wheels, as e e', and a third wheel, as F, to which the motion of one or the other of said wheels e e' may be communicated, according

as said lever E is moved by magnet D or magnet D', and the power or speed controlling device of the motor which drives the generator supplying said current, said wheel F being connected with said power or speed controlling device, substantially as specified.

4. The combination, with a relay-controlling magnet, B, connected with the circuit the current on which is to be regulated, of two operating-magnets, D and D', included in normally-open circuits adapted to be closed by said relay, rocking lever E, friction-wheels e and e', friction-wheel F, shaft f, gear f', hollow internally-threaded gear f², externally-threaded sleeve f³, stops f⁵ and f⁶, spring f⁷, and valve-stem a, substantially as specified.

5. The combination of relay-magnet B, having armature or switch-lever b, contacts b' and b'', with magnets D and D', rocking lever E, wheels e and e', intermeshing gears e² and e³, and wheel F, engaging one or the other of said wheels e e', according as said lever E is tilted in one direction or the other, and the power or speed controlling device of the motor which drives the generator supplying said current, said wheel F being connected with said power or speed controlling device, substantially as specified.

EDWARD H. AMET.
